UNITED STATES PATENT OFFICE.

JAMES STEEL, OF LIVERPOOL, ENGLAND.

LACE.

1,368,853.

Specification of Letters Patent. Patented Feb. 15, 1921.

Application filed December 29, 1917. Serial No. 209,493.

To all whom it may concern:

Be it known that I, JAMES STEEL, a subject of the King of England, residing at 21 Huntly road, Elm Park, Fairfield, Liverpool, in the county of Lancaster, England, secretary, have invented certain new and useful Improvements in or Relating to Laces, of which the following is a specification.

10 This invention relates to laces for boots, shoes, and the like, of that type in which a head or enlargement is formed or provided on or at one end of the lace for the purpose of stopping or preventing it from passing 15 completely through an eyelet.

A lace, according to my invention, is characterized in that there is formed or provided at one end a flat or disk-like head, a portion of the lace proper being formed out of 20 the disk by cutting or opening thereinto in a direction toward the middle or center thereof; in other words the lace proper when pulled out at approximately right angles to the disk—as when applied to a boot—commences 25 at the base of the slot formed in the disk by the incisions therein; thus said disk will lie evenly and flatly against the interior wall of the boot and not cause any discomfort to the foot.

30 A lace with stop-disk, according to my invention, may obviously be formed of suitable substances other than leather or the like; as, for instance, it may be made of mon-hair or other woven material.

35 In some cases said disk may be stiffened or hardened by dipping in a suitable indurating solution.

I will further describe my invention with the aid of the accompanying sheet of explanatory drawings in which:—

40 Figures 1 and 2 illustrate the application of the lace to a boot, Fig. 1 showing said boots partially laced and Fig. 2 showing it completely laced.

45 Fig. 3 shows in front and side elevation the head end of the lace, drawn to an enlarged scale as compared with Figs. 1 and 2, and prior to its application to a boot or shoe.

50 Fig. 4 shows in front elevation, side elevation and plan view, the relative positions

of the head and lace proper when inserted in a boot.

Referring first more particularly to Figs. 3 and 4, *a* represents the disk-like head of a 55 leather lace and *b* *b*¹ is the lace proper, portion *b*¹ whereof is formed out of the disk *a* by cutting into the latter; thus when the lace is fitted in the boot the parts assume the position shown in Fig. 4, disk *a* lying flatly 60 against the boot wall.

Referring now more particularly to Figs. 1 and 2, which illustrate the method of lacing:—

The lace is inserted through one of the 65 bottom eyelets so that the disk *a* lies flatly between the tongue and boot upper; the lace is then threaded through all the eyelets in the ordinary way and the free end *b*³ is brought to the boot top, the part *b*⁴ immediately above the two top eyelets being allowed to hang loose (Fig. 1).

With this loose lace portion *b*⁴ the lacing is continued on the hooks left and right, missing each alternate hook, on both sides, 75 until the top of the boot is reached. The lacing is then continued downwardly on the vacant hooks, when the free end *b*³ is pulled taut and passed inside the top of the boot, (Fig. 2). To unloosen the lace, it is merely 80 necessary to pull up that portion of it between the top eyelet and bottom hook and undo in the usual manner.

Having now described my invention what I claim is new and desire to secure by Letters Patent is:—

A lace having an integral circular head at one end thereof and said head provided with slits alining with the side edges of the lace and extending to the diameter of said 90 circular head which is at a right angle to said lace so that the end of the lace is a portion removed from the head and said head may be bent at a right angle to the lace.

In testimony whereof I affix my signature 95 in the presence of two witnesses this 25th day of September, 1917.

JAMES STEEL.
